DESCRIPTION

U.S. PATENT DOCUMENTS

FIG. 1 is a top and front perspective view of a housing for variable electric power probe showing my new design;
FIG. 2 is a bottom and rear perspective view thereof;
FIG. 3 is a front elevational view thereof; and,
FIG. 4 is a rear elevational view thereof.

The probe and the power cord shown by phantom lines in FIG. 1 are for illustration only and form no part of my design.
